UNITED STATES PATENT OFFICE.

LESTER CERF, OF NEW YORK, N. Y.

ADDING-MACHINE.

SPECIFICATION forming part of Letters Patent No. 749,473, dated January 12, 1904.

Application filed October 17, 1903. Serial No. 177,446. (No model.)

To all whom it may concern:

Be it known that I, LESTER CERF, a citizen of the United States of America, residing at the borough of Brooklyn, city of New York, 5 in the county of Kings and State of New York, have invented certain new and useful Improvements in Adding-Machines, of which the following is a specification.

My invention has reference to improvements in adding-machines, and particularly to an adding mechanism which can be readily attached to or connected with an ordinary type-writing machine.

My invention has for its objects to provide 15 an adding mechanism of a simple construction which is not liable to get out of order and is adapted for high speed with extreme accuracy.

To this end my invention consists, essentially, in an adding-machine comprising a carrier rotatably mounted, a series of interconnecting registering devices on said carrier arranged concentrically with its axis, an actuating mechanism adapted to engage with and operate the individual registering devices, and means for imparting a step-by-step movement to said carrier for presenting the registering devices successively to the actuating mechanism, and also in a combined type-writing and 30 adding machine comprising a motor-impelled carrier rotatably mounted, a series of interconnecting registering devices on said carrier arranged concentrically with its axis, an actuating mechanism adapted to engage with and operate the individual registering devices, and means for imparting a step-by-step movement to said carrier for presenting the registering devices successively to the actuating mechanism, and said mechanism placed in operative connection with the numeral finger-keys through devices giving variable throw to the actuating mechanism, and said keys operating the types.

The nature of my invention will best be understood when described in connection with the accompanying drawings, in which—

Figure 1 represents a side elevation of a type-writing machine with my improved adding mechanism attached. Fig. 2 is a front elevation of the same. Fig. 3 is a face view,

on an enlarged scale, of the adding mechanism with the counter removed. Fig. 4 is a face view showing the parts of the adding mechanism in positions differing from those shown in Fig. 3 and the counter replaced. Fig. 5 is a 55 rear view of a detail part of the counter, part being broken away. Fig. 6 is a face view of part of the pallet-lever of the escapement. Fig. 7 is a vertical section on the line 6 6, Fig. 4. Fig. 8 is an end elevation of the finger-key cams and shaft. Fig. 9 is a plan view of the same, drawn to a smaller scale.

Similar letters and numerals of reference 65 designate corresponding parts throughout the several views of the drawings.

Referring now to the drawings, the letter A designates what I shall herein term the "counter," the same comprising a carrier and the elements necessary for registering and adding when the counter is operated by the actuating mechanism of the machine. The carrier is rotatably mounted upon a spindle *a*, secured to the frame B of the machine, and carries a series of ratchet-wheels *b' b² b³*, &c., arranged in a circle concentric with the spindle *a* and each provided with ten teeth. These ratchet-wheels are engaged by suitable spring-pawls *c* for preventing retrograde motion, and on the arbors *d* of the former are rigidly mounted gear-wheels *e*. These gear-wheels *e* engage 70 with a circular series of intermediate gears *f*, each having one long tooth, as usual in counters, for the purpose of advancing the succeeding registering-hand through one space when the preceding hand is turned through ten 75 spaces. To the ends of the arbors *d* are affixed registering-hands *g*, arranged adjacent to the respective dials *h' h² h³*, &c., affixed to or forming part of the face of the carrier.

It will be readily understood from the foregoing that if any one of the ratchet-wheels *b' b²*, &c., is turned the corresponding registering-hand *g* is moved over its dial *h' h²*, &c., through a corresponding distance. The ratchet-wheels *b' b² b³*, &c., are adapted to be 95 successively engaged when brought to a predetermined point by a ratchet-bar C, the teeth of which are sufficient in number to completely turn the corresponding ratchet-wheel on a complete forward stroke of said bar, while on 100

the return stroke the bar passes over the teeth without affecting the respective wheel. The bar in the present instance is secured at 1 to a lever-arm 2, hinged at 3 to a slide 4, guided in 5 suitable ways in the frame B. The lever 3 is pressed toward the counter and against a suitable stop 5 by a spring 6, and in this position the ratchet-bar C is in line with the teeth of the respective ratchet-wheel $b' b^2 b^3$, &c., and 10 will turn the same when moved downwardly. A spring 7, preferably in the form of a spiral spring attached at one end to a circular hub on the frame 3 and at its other end to a pin 8, projecting from the rear of the slide 4 and passing 15 through a slot 9 in the frame B, tends to hold the slide in its upper or normal position. The slide is drawn downwardly to actuate the ratchet-wheel of the counter by a suitable mechanism placed in connection with the finger-keys. This mechanism will be described 20 presently.

The counter A is advanced in a step-by-step movement to bring the ratchet-wheels $b' b^2 b^3$, &c., successively before or in alignment with 25 the ratchet-bar C when the slide is finishing its upward stroke by the following means, (see Figs. 3, 5, and 7:) The carrier A is subjected to the action of a spiral spring 10, having one end secured to the spindle a and its 30 other end to a hub 11 on said carrier and said spring tending to turn the carrier in the direction of arrow 1, Figs. 4 and 5. Of course the carrier, and consequently the counter A, may be impelled by any other suitable motive 35 force. This movement of the carrier is controlled by an escapement, Figs. 3, 4, and 7, consisting of a pallet-lever 12, hinged at 13 to the frame B and provided at its lower end with a pallet 14, having therein a passage- 40 way 18. This pallet is disposed in the path of a double series of staggered pins 16 and 17, circularly arranged on the carrier, and is adapted to alternately engage with one or the other of each set of pins. When the pallet- 45 lever is in the position shown by full lines in Fig. 3, the pin 16 of one set rests upon the pallet 14 close to the edge of the passage-way 18, and when the lever is moved to the position indicated by broken lines the pin 16 50 passes through the passage-way, and the carrier turns through a slight distance, whereupon its motion is arrested by the pin 17 engaging with the pallet 14. When the lever returns to its normal position, (full lines,) pin 55 17 passes through the passage-way 18, and the carrier turns through one complete step, whereupon its motion is arrested by the pin 16 of the next succeeding set of pins engaging with the pallet. The inner side of the pallet 60 14 is inclined downwardly and outwardly, so that when the counter is turned in a direction reverse to that indicated by the arrow by hand the pins 16 and 17 can pass through the passage-way by forcing the pallet to one side. 65 The carrier has also a projecting stop 24,

adapted to engage with the pallet 14 and entirely arrest the advance movement of the counter. In this position of the counter the ratchet-wheel b' , corresponding to the units-dial l' , is in alignment with the ratchet-bar 70 C, and its teeth are adapted to be engaged by the same. This position is the normal position of the counter and is indicated by two fixed marks $j j$ on the counter and on its frame, as indicated in Fig. 2. Near its upper end 75 the pallet-lever 12 is provided with a pallet 19, which is adapted to be engaged by a trip 20, formed on or secured to the top of the slide 4, and the upper end of the pallet-lever is also adapted to be engaged by an anchor 21, provided for this purpose with a shoulder 22, and said anchor is also provided with a projecting nib 23, arranged in the path of the trip. A spring 15 normally holds the pallet-lever 12 in the position shown by full lines in 80 Fig. 3.

The downward movement of the slide 4 for effecting the propulsion of the ratchet-bar C may be induced by a usual series of keys and key-bars, such as are employed in type-writing or adding machines. In Figs. 1 and 2 I have shown a shaft D placed below the series of key-bars k and provided with a series of inwardly-projecting key-cams $m^0 m^1 m^2$, &c., located beneath and adjacent to the key-bars 90 of the respective numeral-keys $l^0 l^1 l^2$, &c., Figs. 8 and 9. The finger-key cams are of different curvatures, and said curvature increases from the cam m^0 to the cam m^2 , the finger-key cams being so disposed that when 100 the key l^0 is depressed the ratchet-bar C is moved a linear distance sufficient to turn the ratchet-wheel b' through one tooth. When the finger-key corresponding to the key-bar l^2 is depressed, the ratchet-wheel b' is turned 105 through two teeth, &c. The finger-key cam m^0 only moves the slide 4 a sufficient distance to trip the escapement and causes no operation of the corresponding ratchet-wheel. The shaft D is provided with an inwardly-projecting arm 25, connected by a link 26 with a pin 8, attached to the slide 4. A suitable stop-rail 28, located beneath the key-bars, limits the 110 downward movement of the same.

The counter can be turned in a direction opposite to that indicated by arrow 1, Fig. 4, by means of a head 27, connected to a hub on the carrier, for the purpose of setting any one of the dials opposite to the ratchet-bar C, thus throwing the corresponding ratchet-wheels 115 into alignment with said ratchet-bar.

I will now proceed to describe the operation of the machine as here presented. Assuming the mechanism to be in its normal position—that is, with the counter in the position shown in Fig. 2, where the marks $j j$ register and the units-wheel b' is in alignment with the ratchet-bar C, which latter is in its upper position, and the pin 16 of the carrier is in engagement with the pallet 14 of the lever 120 130

12—let the following numbers be added—to wit., "7,560" and "943." The first number having four integers, the counter is turned through four dials to the left, thus bringing 5 the thousands ratchet-wheel b^4 in alinement with the ratchet-bar C. The finger-key corresponding to key-bar k^7 is then depressed. The depression of this key turns the key-cam k^7 downwardly, and in view of the connection 10 of the shaft D with the slide 4 the latter is drawn downwardly a sufficient distance to turn the ratchet-wheel d^4 through seven teeth and the corresponding registering-hand points to "7" on the thousands dial. During the 15 first small part of the downward movement of the slide 4 the trip 20 thereon engages with the pallet 19 on the pallet-lever 12 and turns the same into the position shown in Fig. 3 by dotted lines, thus permitting the pin 16 20 on the counter-casing to pass through the passage-way 18 in the pallet 14. This allows a slight angular movement of the counter, which is limited by the engagement of the pin 17 with the pallet 14. The pallet-lever is held in this position 25 by the shoulder 22 of the anchor 21 engaging with the same, as shown in Fig. 4, during the remaining downward stroke of the slide 4. The counter therefore remains in this slightly-advanced position until after the finger-key has 30 been released and until the slide approaches the end of its upward stroke under the influence of the spring 7, when the trip 20 engages with the nib 23 of the anchor 21 and releases the pallet-lever from the same, thus allowing 35 it to return to its normal position under the influence of its spring. In this position the pin 17 can pass through the passage-way 18 in the pallet 14 and the counter turns through one step—that is, until the next pin 16 engages 40 with the body of the pallet. This movement brings the next dial h^3 in alinement with the ratchet-bar C. The key of key-bar k^5 is now depressed and released with a repeated operation of the mechanism, and the tens ratchet- 45 wheel b^3 is advanced into alinement with the ratchet-bar C. On the depression and release of the finger-key 6 the operation is again repeated and the units ratchet-wheel is in alinement with the ratchet-bar C, and further rotary motion of the counter is arrested by the 50 pin 24 engaging the pallet. The last numeral being a cipher, the depression of the finger-key k^0 has no effect upon the ratchet-wheel b^1 . If the cipher were in the hundreds or other 55 higher place, the slight movement of the slide is just sufficient to release the counter, so as to bring the next dial into position. The dials on the counter now register "7560." To add thereto "943" the same operation is repeated, 60 the counter first being set to bring the hundreds ratchet-wheel in line. After completed operations the dials then register "8503." The types t are actuated to print the numerals, as usual.

65 To provide for the disengagement of the

counter when it is not desired to add while writing, I provide a suitable cut-out, such as the lever 30, pivoted to the frame B, to which the spring 35 is attached, and said lever being provided with a toe adapted to engage a 70 notched spring-catch 31. By turning the lever 30 to the right the lever 2, carrying the ratchet-bar C, is moved over to throw the latter out of alinement with the ratchet-wheels b^1 b^2 b^3 , &c. The notches in the catch 31 hold 75 the lever in either of its terminal positions.

While I have herein shown the adding mechanism in connection with and operated by a type-writing machine, it is of course to be understood that the counter and its actuating 80 mechanism may be used in connection with a set of usual finger-keys and the printing of the numerals dispensed with, as in ordinary adding, calculating, or totalizing machines. I wish it also to be distinctly understood that the 85 specific actuating mechanism for the counter may be changed or altered without departing from the spirit of my invention, as the latter consists, essentially, in the planetary arrangement of the dials. It is also to be understood that in place of the dials and registering-hands the usual registering-wheels and sight-openings in the cover of the casing can be used, or any other known suitable form of indicating 90 devices can be substituted.

95 What I claim as new is—

1. An adding-machine comprising a carrier rotatably mounted, a series of interconnecting registering devices on said carrier arranged concentrically with its axis, an actuating mechanism adapted to engage with and operate the individual registering devices, and means for imparting a step-by-step movement to said carrier for presenting the registering devices successively to the actuating mechanism, substantially as described.

100 2. An adding-machine comprising a carrier rotatably mounted, a series of interconnecting registering devices on said carrier arranged concentrically with its axis, an actuating mechanism adapted to engage with and operate the individual registering devices, and means for imparting a step-by-step movement to the carrier for presenting the registering devices successively to the actuating mechanism controlled by said actuating mechanism for the registering devices, substantially as described.

110 3. An adding-machine comprising a motor-impelled carrier rotatably mounted, a series of interconnecting registering devices on said carrier arranged concentrically with its axis, an actuating mechanism adapted to engage with and operate the individual registering devices, and an escapement controlling the movements of the carrier operated by the actuating mechanism for the registering devices, substantially as described.

120 4. An adding-machine comprising a motor-impelled carrier rotatably mounted, a series of interconnecting registering devices on said car-

rier arranged concentrically with its axis, a series of finger-keys, an actuating mechanism in connection with said keys and adapted to engage with and operate the individual registering devices, and an escapement for the carrier operated by the actuating mechanism for the registering devices for permitting a step-by-step advancement of the carrier under the influence of its motor, substantially as described.

5. An adding-machine comprising a carrier rotatably mounted, a series of interconnecting registering devices on said carrier arranged concentrically with its axis, means for imparting rotary movement to the carrier, a double series of staggered pins projecting from the carrier, a pallet-lever having a passage-way for the pins, an anchor adapted to engage with said pallet-lever, and actuating means adapted to engage with and operate the individual registering devices and adapted to engage with the pallet-lever and the anchor for releasing the carrier from the pallet-lever for its step-by-step advancement, substantially as described.

6. An adding-machine comprising a carrier rotatably mounted, a series of interconnecting registering devices on said carrier arranged concentrically with its axis, an actuating mechanism adapted to engage with and operate the individual registering devices, means controlled by the actuating mechanism for the registering devices for imparting a step-by-step movement to the carrier, a series of finger-keys, one for each registering device, and operative connections between said keys and the actuating mechanism for imparting different throw to the latter, substantially as described.

40 7. An adding-machine comprising a carrier rotatably mounted, a series of interconnecting registering devices on said carrier arranged concentrically with its axis, and each provided with a ratchet-wheel, a ratchet-bar mounted to reciprocate, means for imparting a step-by-step movement to the carrier for bringing the ratchet-wheels successively in line with the ratchet-bar, and operative means in connection with the ratchet-bar for imparting different throw to the latter, substantially as described.

45 8. In a combined type-writing and adding

machine, the combination of a motor-impelled carrier rotatably mounted, a series of interconnecting registering devices on said carrier arranged concentrically with its axis, an actuating mechanism adapted to engage with and operate the individual registering devices, means for imparting a step-by-step movement to said carrier for presenting the registering devices successively to the actuating mechanism, an operative connection between said mechanism and the numeral finger-keys giving different throw to the actuating mechanism, and an operative connection between said keys and the types, substantially as described.

50 9. An adding-machine comprising a carrier rotatably mounted, a series of interconnecting registering devices on said carrier arranged concentrically with its axis, and each provided with a ratchet-wheel, a swinging ratchet-bar mounted to reciprocate, means for imparting a step-by-step movement to the carrier for bringing the ratchet-wheels successively in line with the ratchet-bar, a stop for arresting the motion of the carrier when the units ratchet-wheel is in line with the ratchet-bar, and operative means in connection with the ratchet-bar for imparting different throw to the latter, substantially as described.

55 10. In a combined type-writing and adding machine, the combination of a motor-impelled carrier rotatably mounted, a series of interconnecting registering devices on said carrier arranged concentrically with its axis, an actuating mechanism adapted to engage with and operate the individual registering devices, means for imparting a step-by-step movement to said carrier for presenting the registering devices successively to the actuating mechanism, an operative connection between said mechanism and the numeral finger-keys giving different throw to the actuating mechanism, an operative connection between said keys and the types, and means for throwing the actuating mechanism out of action, substantially as described.

60 In testimony whereof I have hereunto set my hand in the presence of two subscribing witnesses.

LESTER CERF.
